UNITED STATES PATENT OFFICE

2,131,791

ELECTRIC TARGET RIFLE RANGE

Alva J. Carter, Chicago, Ill., assignor to Rayolite Rifle Range Company, Chicago, Ill., a corporation of Oklahoma

Original application June 15, 1936, Serial No. 85,246. Divided and this application October 7, 1936, Serial No. 104,468

2 Claims. (Cl. 273—101.1)

My invention relates to an improvement in target rifle ranges of the type in which a rifle or revolver or gun or the like is employed to shoot a flash or ray of light, of short duration, at a target which includes a photoelectric cell.

One purpose of my invention is to provide an improved range of the type above described, in which the photoelectric cell is mounted on a moving target.

10 Another purpose is the provision of improved means for connecting the photoelectric cell on the target with an amplifier normally fixed in relation to the housing in which the moving target portions are housed.

15 Another purpose is the provision of improved means for counting the shots fired or the trigger pulls in order to limit the number of trigger pulls available, in a coin operated machine, for each coin insertion.

20 Another purpose is the provision of improved scoring means or score recording means.

Another purpose is the provision of improved means for controlling the drop portion of the target whereby, when the photoelectric cell of the target is struck, a drop, which may simulate a bird or animal, falls to indicate a hit.

This application is a division of my application for an electric target rifle range, filed on June 15, 1936, Serial No. 85,246.

25 Other purposes will appear from time to time in the course of the specification and claims.

I illustrate my invention more or less diagrammatically in the accompanying drawings wherein:

30 Figure 1 is a general wiring diagram with some of the operating parts included;

Figure 2 is a perspective view of the device as a whole;

Figure 3 is a partial interior view of the target structure, looking from the rear;

Figure 4 is a section on the line 4—4 of Figure 3;

Figure 5 is a section on the line 5—5 of Figure 4;

40 Figure 6 is an illustration of the upper portion of Figure 4 with parts in a different position; and

Figure 7 is a view of the score indicating device, illustrated as a part of the wiring diagram in Figure 1, showing parts in different position.

45 Like symbols indicate like parts throughout the specification and drawings.

50 Referring first to Figure 2, A generally indicates the target housing or cabinet; B indicates the firing stand; and C indicates generally the gun structure. It will be understood that the

conductive connections shown in detail in Figure 1 extend between the cabinet and the firing stand and the gun and will be later pointed out in detail. It will be understood that these various connections are carried in flexible conduits or cables, one such cable D connecting the cabinet A with the gun stand B, and a second E, connecting the gun stand B and the gun C.

Referring to the operative parts of the device, and considering first the cabinet structure, generally indicated as at A, I illustrate an outer housing 1, details of which do not per se form part of the present invention. It will be understood, however, that either an open space or a transparent window 2 is employed. To the rear of this window is any suitable scenic foreground indicated as 3, an upper portion of which is generally arcuate to conform to the path of the target structures below described. However, it will be understood that the details of the scenery and the supporting structure therefor may be widely varied.

Mounted within the housing on any suitable support 4 I illustrate a target base 5 which may be bolted in position as by the bolts 6. It supports any suitable bearing construction or sleeve 7, in which is rotatably mounted the target carrying shaft 8. Keyed or otherwise secured to this shaft 8 is a worm gear 9 in mesh with a worm 10 which may be associated with or driven by any suitable motor 11. It will be understood that when the motor 11 is connected in conductive circuit with a source of electric power it serves to rotate the shaft 8 and the parts connected thereto.

Secured to the opposite end of the shaft 8 is a hub 12 to which are secured radial arms 13, 14. Pivoted to the outer end of each said arm, as at 15, is a drop structure generally indicated as 16, with which is associated the weight 17. The drop 45 is apertured as at 18 and may be in the form of a bird or animal. Secured on the outer end of each of the target arms 13, 14 is a target bracket generally indicated as at 19 to the upper end of which is mounted an angle support 20 upon which is positioned any suitable housing 21 within which is positioned a photoelectric cell 22 or any other suitable element for responding to the flash of light diagrammatically indicated in Figures 1 and 6 by the dotted arrow lines 23.

It will be understood that in the operation of the device, the aperture 18 is generally horizontally aligned with the photoelectric cell 22 whereby the user, employing a light projecting gun, can sight through the aperture 18 and hit the 55

cell 22. Any suitable lens portion 24 may be employed in order to concentrate the light from the gun upon the cell. Mounted upon the bracket 19 is an upstanding pivotal member 25 to which is pivoted any suitable latch member 26 slotted at its rear end as at 27 and provided with a latch hook 28 at its forward end. A spring 29 tends normally to draw the latch member into latch holding position, as shown 10 in Figure 4, whereby the drop 16 is normally held in the upright position in which it is shown in Figure 4. I may also employ with the latch a kick-off member 30 adapted, when the latch is lifted into the position in which it is shown in 15 Figure 6, to give a thrust against the back of the target drop structure at the time that the latch is released.

Downwardly extending through a bearing or centering sleeve 31 in the bracket 19 is any 20 suitable actuating member or stem 32, which is provided with adjustable abutments 33, 34, at its lower end, which may be screw-threaded in relation to it and which receive between them the armatures 35 or 35^a associated with the electromagnets 36 or 36^a in any suitable fashion upon 25 a lower portion of the arms 13 or 14. It will be understood that the armature may be slotted as at 37 in order to prevent any binding of the parts when the armature 35 is rotated through its permitted arc of movement in response to excitation of the electromagnet 36. The downward movement of the armature may also be limited by any suitable abutment 38. The slotting of the latch 26, as at 27, similarly prevents binding at 30 the upper end of the rod 32.

It will be understood, of course, that I may provide a wide variety of means for releasing the drop and for holding it in position until 40 released, but the above described structure is practical and operative.

The drop members 16, once they have been released by action of the electromagnets 36, 36^a and rod 32, releasing the catch 26, are returned to initial position by gravity, as the arms 13 45 rotate to position below the axis of rotation of the shaft 8. In order to insure the return of the drops 16 to vertical position, I may also employ a guide or cam member shown in Figure 3 and indicated as 200. The lower end may be rounded or beveled as at 201 in order to throw the drop member 16 into vertical position, in which position it is again received and held by the locking means shown in Figure 4 and including the latch 26.

55 In order to include the photoelectric cell 22 in a conductive circuit with parts which do not move with the movable portion of the target, I provide a hub or sleeve member of non-conductive material, generally indicated as 40. Mounted 60 in the outer surface of this hub are three complete slip rings 41, 42 and 43, and a pair of segments 44, 45, which together make a practically complete ring but are insulated from each other. Opposed to each of these rings, and to the segments, is an individual conductive contact finger illustrated as 41^a, 42^a, 43^a and 46. As will be clear from Figure 4, two of these conductive fingers are positioned above and two below the axis of rotation of the shaft 8 and they are 65 mounted for example in blocks 47 of non-conductive material and are normally stationary.

70 Referring to the gun structure as shown in Figure 1, I may employ any suitable gun stock generally indicated as 50 having a barrel 51 and sights 52. Mounted in the barrel, preferably at 75

the rear end thereof, is an incandescent lamp 53. In circuit with the lamp is a mercury controlled switch generally indicated as 54. Any suitable lens or lenses 55 may be employed to direct a relatively restricted light beam from the gun. 5 I illustrate only one, in Figure 1, but more may be employed if necessary. 56 illustrates a trigger pivoted as at 57 and having an inward extension within the gun.

Pivoted to this inward extension is a stem 59 10 which is provided with a knob 62 of insulating material.

Positioned above the trigger structure is a longitudinally movable stem 72 with a cone-shaped portion 73 intermediate its ends. 15

Pivoted in the aperture 85 in the bottom of the gun barrel 51 is a pivoted shutter 87.

The details of the gun mechanism are only diagrammatically illustrated in Figure 1 since 20 they form no part of the present invention.

A brief description of the gun mechanism is as follows: Each time the trigger 56 is pulled, it actuates the movable stem 72 which in turn, by means of the cone-shaped portion 73, momentarily opens the shutter 87. 25

The shutter 87, which normally masks the light 53, thus permits a beam of light to escape from the gun barrel 51.

The trigger pull has an additional function, 30 namely that of closing the gun switch which includes the opposed switch spring contacts 100 and 100^a. This result is obtained by the engagement of the knob 62 with the outer end of the leaf 100, as shown in Figure 1, the knob 62 being of insulating material. 35

Referring now to the general schematic circuit layout, as shown in Figure 1, I illustrate terminal lines *a* and *a*¹. The terminal line *a* connects to one side of the coil *a*³ of a transformer generally indicated as *T*. A switch *a*² is shown which may 40 be manually operable to terminate the operation of the entire machine. The line *a*¹ extends to the opposite terminal of the primary coil *a*³. In parallel across the lines *a*, *a*¹ is the line *a*⁴ in which is the motor 11. *a*⁵ indicates any suitable switch 45 which may be manually operated whereby, when the switch *a*² is closed, the motor can still be switched on and off at will.

I illustrate one secondary coil for the transformer *T*, at *a*⁶, which may for example be of 50 small voltage, 6 volts being satisfactory. From one terminal extends the conductive line *a*⁷ to the gun lamp 53. From the other terminal the conductive line *a*⁸ extends to the opposite terminal of the gun lamp 53. Interposed in it is the 55 mercury switch 54 which is adapted to prevent a closure of the gun lamp circuit unless the gun is in substantially horizontal position.

I may employ a second secondary coil or coils of the transformer *T* generally indicated as *b*. 60 From one terminal extends the conductive line *b*¹ to *b*². Extending from the junction *b*² is the line *b*³ to one terminal *b*⁴ of the coin operated switch generally indicated as *S*. Any suitable means *S*¹ may be employed in response to the insertion of a coin, or at the time of the insertion of the coin, to move the switch *S* into closed position. From the opposite terminal *B*⁵ of the switch extends the conductive line *b*⁶ to the electromagnet *b*⁷. From the electromagnet *b*⁷ the 70 line *b*⁸ extends to the junction *b*⁹ and the conductive line *b*¹⁰ completes a circuit to the opposite terminal of the secondary coil *b* of the transformer *T*.

Extending from the junction *b*¹¹ in the line *b*¹ 75

is a line b^{12} to the switch contact 100 of the gun switch. The circuit then extends from the opposite terminal 100^a by means of the line b^{13} to the switch contact b^{14} . The opposite contact b^{15} is connected by the conductive line b^{16} to the line b^6 .

The above described connections form a shunt connection to actuate the electromagnet b^7 .

Associated with the electromagnet b^7 is the armature 110 pivoted as at 111 and provided with a spring hammer 112 opposed to any suitable sounding abutment 113 which may, if desired, be a portion of the cabinet. The armature also includes an upwardly extending portion 114 to which is pivoted as at 115 a dog 116 opposed to a cam disc 118 , both being mounted on a shaft 119 , the cam being provided with a cam notch 120 adapted to receive a portion of the contact b^{15} whereby, when the contact b^{15} is aligned with the cam notch 120 , the conductive contact between the switch members b^{14} and b^{15} is broken. A spring 121 tends normally to hold the dog 116 down against the ratchet and the spring 122 tends to hold the armature as a whole against the stop 123 .

It will be observed that eleven teeth are shown on the ratchet 117 . When the coin switch S is closed, upon the insertion of a coin, the electromagnet b^7 is energized and the armature is moved counter-clockwise. This causes the dog 116 to ride over one tooth. The next time the circuit is broken the spring 122 is effective to move the ratchet wheel the distance of one notch. This moves the notch 120 out of engagement with the spring switch contact b^{15} and closes the switch.

The operator, having inserted his coin, next takes aim and pulls the trigger 56 . This closes the switch leaves 100 and 100^a and again closes the circuit through the electromagnet b^7 through the shunt circuit above described, and this again moves the armature 114 and the dog 116 over one notch, and again permits the spring 122 to withdraw the armature and rotate the ratchet the distance of one tooth. Inasmuch as the notch 120 has already cleared the switch b^{15} , the switch contacts b^{14} and b^{15} are left closed.

Another result of the trigger pull is the thud caused by the impact of the hammer 112 against the opposed abutment 113 which simulates or suggests the sound of a shot, and which takes place at each trigger pull.

After the tenth trigger pull, the notch 120 is again in line with the off-set portion of the switch leaf B^{15} and permits that switch to swing out of contact with the opposed switch b^{14} . This breaks the shunt connection between the trigger switch 100 and 100^a , and the insertion of another coin is necessary to start the device.

The amplifier circuit and the circuit for the scoring or score recording device may be described as follows:

The photoelectric amplifier cooperates with the photoelectric cells 22 and 22^a when one of the photoelectric cells is struck by a flash of light from the gun C as generally indicated, as in Figure 1, by the letter P . It will be understood that the power for the amplifier is received from the commercial power circuit including the lines a and a^1 , which operate the transformer T .

From the secondary coil b a line may be traced through b^1 , b^2 , c , to the switch member c^1 , the opposed switch member c^2 , the line c^3 , passing the intersection point c^4 and terminating at

the amplifier P as at c^5 . The circuit for the amplifier is completed from the contact c^6 , line c^7 , to the junction c^8 , and back along the line b^{10} to the opposite terminal of the secondary coil b of the transformer T .

As will be clear, for example from Figure 1, a switch including the elements c^1 and c^2 is closed by the action of the member b^{14} and b^{15} when the member b^{15} is moved out of the notch 120 in the cam disc 118 . This is to say, the switches b^{14} , b^{15} and c^1 , c^2 , are operated in unison in response to movement of the cam disc 118 . When the switch members c^1 , c^2 are closed, the photoelectric amplifier P receives power from the secondary coil b of the transformer T and is ready to function.

The connection between the photoelectric cell 22 and 22^a and the photoelectric amplifier P is as follows:

Tracing from the contact or terminal c^9 is the line c^{10} to the fixed contact 42^a in contact with the ring 42 . Extending from the ring 42 is the conductive line c^{11} to the junction c^{12} where it branches as c^{13} , c^{14} to the photoelectric cells 22 and 22^a , respectively. Return lines c^{15} and c^{16} are provided from the two photoelectric cells which join at the junction c^{17} with the line c^{18} which extends to the ring 43 . 43^a is another fixed contact opposed to the ring 43 and from it extends the conductive line c^{19} to the terminal c^{20} on the photoelectric amplifier.

The result of the impingement of a flash of light upon the photoelectric cells 22 or 22^a is to excite the photoelectric relay d which, when excited, closes the moving switch contact d^1 against the fixed contact d^2 . The circuit so controlled may be traced from the secondary coil b of the transformer T through the line b^1 to the junction d^3 , along the line d^4 to the junction d^5 along the line d^6 to the electromagnet d^7 , and thence along the line d^8 to the junction d^9 , and, by the line d^{10} , to the fixed switch member d^2 . In other words, a circuit is closed which excites the electromagnet d^7 and moves the armature d^{11} which, when moved, lifts the lever arm d^{12} and moves the dog d^{13} against the ratchet d^{14} and advances the scoring drum d^{15} one step. Thus at each actuation of the electromagnet d^7 and the armature d^{11} , the drum d^{15} is advanced one unit, each unit being given an appropriate number, and the total number of advances of the drum d^{15} equalling the total number of hits made against one or the other of the photoelectric cells 22 or 22^a . The score indicator is visible through the window d^{16} , in the front of the cabinet shown in Figure 2.

It will be understood that a spring d^{17} tends normally to keep the armature in the position in which it is shown in Figure 1. The spring d^{18} is to keep the dog d^{13} in the position in which it is shown against the stop d^{19} . The function of the spring d^{20} is to cause the drum d^{15} and its associated parts to return to initial position, which movement is normally resisted by the detent d^{20} , held in the position in which it is shown by the spring d^{21} of Figure 1.

The circuit controlled by the relay d and the switch members d^1 and d^2 is continued from the switch d^1 by the line d^{22} to the junction d^{23} and by the line d^{24} to the junction c^8 where it joins the line b^{10} .

In order to reset the drum d^{15} to initial position I provide the following circuit which branches from the line c^3 at the junction c^4 as follows:

The line e extends from the junction c^4 to the

electromagnet e^1 and continues by the line e^2 to the junction d^{23} and through the line d^{24} to the junction c^8 , and line b^{10} which closes the circuit through the secondary coil b of the transformer 5 T and through the switch elements c^1 , c^2 of the shot limit structure. As long as the switch structure c^1 , c^2 , that is to say, as long as the switch member b^{15} is riding on the periphery of the cam disc 118 and has not yet dropped into the notch 10 120, the circuit through the electromagnet e^1 is closed. At the tenth shot, when the connection between the switch members c^1 and c^2 is broken, and the circuit is broken through the electromagnet e^1 , the armature e^3 is drawn by the 15 spring e^4 into the position in which it is shown in Figure 1, and the latch e^5 slides forward away from the abutment e^6 and its latch or head portion e^7 rides over the pin e^8 on the detent d^{20} in readiness to release the detent d^{20} and to permit 20 the spring d^{25} to rotate the parts back to initial position, any suitable stop means being provided to terminate the retrograde movement of the drum d^{15} when the symbol 0 is aligned with the aperture d^{16} , as shown in Figure 2. When 25 the device is again set in movement by closure of the coin operated switch S , the electromagnet e^1 is again excited and draws to itself the armature e^3 . When it does so, it moves with it the detent d^{20} , permitting the spring d^{25} to move the drum 30 d^{15} back to the zero position. By the time the detent has cleared the teeth of the ratchet wheel d^{14} , the hump e^9 of the latch e^5 moves over the abutment e^6 , causing the latch e^5 to lift and release the detent d^{20} , to the position in which 35 it is shown in Figure 11. As long as the circuit continues closed through the switch members c^1 , c^2 , the parts remain in that position. The detent d^{20} prevents retrograde movement of the ratchet d^{14} , while allowing its forward step by step movement in response to actuation of the armature d^{11} .

In order to actuate the drop structure, shown for example in Figure 4 and including the drop members 16, I provide the already described electromagnets 36 and 36^a, only one of which can work at a time, because of the employment of the split ring segments 44 and 45 already described. The connection there formed from the transformer T and its secondary coil b may be traced by the line d^4 , through the junction d^5 , by the line g to the normally fixed contact 41^a, the ring 41, the line g^1 , through the electromagnet 45 36, back by the line g^2 , to the upper segment 44, the normally fixed contact 46, and the line g^3 50 to the junction d^9 , through the line d^{10} and switch members d^2 , d^1 , back along the line d^{22} , junction d^{23} , the lines d^{24} and b^{10} to the secondary coil b 55 of the transformer T .

Similar lines are shown and similarly indicated, extending to the electromagnet 36^a, in connection with the ring 45. It will be understood however, that only the top drop can ever be shot at and only one can be shot at at a time and only 60 one of the electromagnets 36, 36^a can operate at one time.

It will be realized that, whereas I have described and illustrated a practical and operative device, nevertheless many changes may be made in the size, shape, number and disposition of parts without departing from the spirit of my invention. I 65 therefore wish my description and drawings to be taken as in a broad sense illustrative or dia-

grammatic, rather than as limiting me to the precise showing.

In particular, I wish it to be understood that I am claiming primarily a target range and do not intend to limit myself to the particular circuits employed, since a wide variety of substantially equivalent circuits may be employed, which may differ greatly in general detail and tracing, while obtaining the same, or substantially the same, result. I therefore do not wish to be limited to 10 the specific structure and circuits here shown except to the extent in which I positively limit myself in the language of the claims. I also wish it to be understood that the photoelectric amplifier employed may vary widely, and that it 15 may be practical to put it in continuous circuit and control the motor circuit by the coin switch structure herein shown. In other words, this involves reversing the position of the amplifier and motor in the diagram of Figure 1, a reversal 20 which would be perfectly clear to any skilled operator in the art.

It will be understood, however, that the amplifier employed is not a source of power for operating the structure herein shown but is 25 merely a means of controlling or actuating the elements involved in response to the excitement or closure of the photoelectric amplifier relay as a result of hits recorded against the photoelectric cells. It will be understood, therefore, that a 30 wide variety of changes may be made in the wiring diagram herein shown without departing from the spirit of my invention and scope of my claims.

I claim:

1. A marksmanship device comprising an arm 35 mounted for rotation, a light sensitive cell carried by one end of the arm, a pivoted target plate apertured in register with and carried by the arm and in front of the light sensitive cell, means responsive to energization of the cell for causing the target plate to move into a hit indicating position, including a latch member movable end- 40 wise of said arm and adapted normally to hold said target plate in upright position, means for releasing said latch member in response to the 45 energization of the cell, including a solenoid and a mechanical connection between said solenoid and said latch member, hammer means and means for causing the hammer means to strike the target plate following its release by the latch to 50 positively urge the target plate into hit indicating position.

2. In a target, a hub and means for rotating it, a pair of radial arms spaced one hundred and eighty degrees from each other, extending outwardly from said hub, an independent target upon the end of each of said arms including a target drop pivoted to said arm, said target drop being apertured, photosensitive means associated with said targets whereby when a flash of light passes 60 through the aperture of either of said drops said photosensitive means are affected, latch means adapted normally to hold each said target drop in upright position, a control rod for each said latch means extending inwardly along the 65 arm associated therewith to a point adjacent the hub, electromagnetic means for moving said rods and an actuating circuit therefor, and means for closing said circuit when said photosensitive means are excited.

ALVA J. CARTER.
